MEDICAL HYPODERMIC SYRINGE PISTON

George Coanda, 337 W. Elk, Glendale, Calif.

Filed Oct. 26, 1964, Ser. No. 82,325

Term of patent 14 years

(Cl. D83—12)

FIG. 1.

FIG. 2.

FIG. 3.

FIG. 4.

FIGURE 1 is a perspective view of the medical hypodermic syringe piston showing my new design;

FIGURE 2 is a front elevational view of the medical hypodermic syringe piston;

FIGURE 3 is a rear elevational view of the medical hypodermic syringe piston; and

FIGURE 4 is a cross-sectional side elevational view of the medical hypodermic syringe piston.

The dotted line showing of the plunger handle associated with the medical hypodermic syringe piston is for illustrative purposes only.

I claim:

The ornamental design for a medical hypodermic syringe piston, as shown and described.
